UNITED STATES PATENT OFFICE

2,250,217

CIRCUIT-INTERRUPTING SYSTEM

Eugene W. Boehne, Drexel Hill, Pa., assignor to
General Electric Company, a corporation of
New York

Application February 28, 1940, Serial No. 321,235

5 Claims. (Cl. 175—294)

My invention relates to a circuit interrupting system and more specifically to such a system employing a circuit breaker which depends for its operation at least in part upon a source of fluid under pressure.

Since a circuit-interrupting system must interrupt the circuit at the proper time and in the proper manner, it is essential that the control equipment and associated apparatus cooperating with the circuit breaker to cause its operation do not fail at a crucial time and, if they fail, that additional means be provided for protecting the circuit. Where the operation of the circuit breaker depends to some extent at least upon a source of fluid under pressure, there is always the possibility of a reduction or complete failure of the pressure of this source of fluid so that the protection given by the circuit breaker is nonexistent or at least doubtful. Therefore, means should be provided for insuring the interruption of the circuit in case of an abnormal current condition even though the source of fluid pressure upon which the operation of the circuit breaker depends to a certain extent fails for some reason or other so that the circuit breaker cannot be operated.

It is an object of my invention, therefore, to provide a circuit-interrupting system employing a circuit breaker which depends for its operation at least to some extent upon a source of fluid under pressure, wherein interruption of the circuit under abnormal conditions will occur even though there is a failure of the source of fluid under pressure so that the circuit breaker cannot be operated satisfactorily.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing, the single figure of which is a schematic diagram of the control system for an electric circuit breaker embodying my invention.

For the purposes of explanation, I have illustrated my circuit-interrupting system as employing a circuit breaker of the cross fluid-blast type which is disclosed and claimed in the joint application of David C. Prince, William K. Rankin, and Wilfred F. Skeats, Serial No. 303,126, filed November 6, 1939, and assigned to the same assignee as the present application. It will be understood, however, that this circuit-

interrupting system may employ other types of circuit breakers which depend for their operation to a certain extent at least upon a source of fluid under pressure.

5 Referring now to the drawing, I have illustrated my invention as employing a fluid-blast circuit breaker 10 of the cross-blast type comprising a stationary contact 11 and a movable contact 12 arranged to be operated so as to draw an arc in an arc chute 13. The fixed contact 11 is connected to the line terminal 14 while the movable contact 12 is connected to the line terminal 15. Fixed contact 11 is provided with spring-pressed contact fingers 11a and longer arcing contact fingers 11', while movable contact 12 is provided with an arcing tip 12' so that, when the contacts separate, an arc therebetween occurs between arcing tips 11' and 12'. Immediately after separation of the contacts, 15 one terminal of the arc is transferred by a blast of fluid, preferably air, issuing out of conduit 16, from contact fingers 11' to the contact 11'' which is provided with a tip of arc-resistant metal. The air blast from conduit 16 upon opening of the breaker drives the arc into the arc chute 13 against the edges of a plurality of partitions 17 in the arc chute, which partitions are transverse to the air gap and the ends of which extend close to the path of movement of the 20 arcing tip 12' of the movable contact 12. The circuit breaker 10, illustrated by way of example 25 in order to describe my circuit-interrupting system, is not my invention but is described and claimed in copending application Serial No. 303,126, referred to above.

In order to operate circuit breaker 10 automatically by fluid pressure, there is provided a cylinder 18 with a piston 19 connected through a rod 20 to operate a lever 21 secured to the 30 shaft 22. The shaft 22 has attached thereto an arm 23 of insulating material for operating the movable contact 12 of the circuit breaker. Although circuit breaker 10 is described with respect to a single phase, it will, of course, be understood by those skilled in the art that it may just as well comprise a plurality of phases, in which case, a plurality of arms 23 would be provided for operating the movable contacts 12 of the various phases. The arm 23 is shown 35 provided with a pin 24 operating the member 25 secured to the outer end of movable contact 12. Member 25 is arranged to slide on a pair of rods 26, only one of which is shown in the drawing since the other is obscured from view thereby. 40 It will be apparent that, when the shaft 22 is

rotated in a counterclockwise direction, the arm 23 will move the contact 12 to the open position of circuit breaker 10 and that, when the shaft 22 is rotated in a clockwise direction, the arm 23 will move the contact 12 to the closed position. The member 25 and the rods 26 constitute a kind of cross-head arrangement by which the movable contact is reciprocated. This type of operating mechanism is described in detail in United States Letters Patent 2,218,797, granted October 22, 1940, upon the joint application of Leonard J. Linde and Torild Andersen, and assigned to the same assignee as the present application.

In order to operate the circuit breaker 10 as well as to supply a blast of fluid through conduit 16 for arc-extinguishing purposes, a source of fluid pressure 27 is provided which is preferably air under pressure. This source of air under pressure 27 is connected through a suitable blast valve 28 to conduit 16 for supplying a blast of air adjacent contacts 11 and 12 of circuit breaker 10 for arc-extinguishing purposes. Blast valve 28 is normally biased to the closed position by means of spring 29 and is operated by means of solenoid 30 which may be energized at the desired time by any suitable control circuit. The source of fluid 27 is also connected with the respective ends of cylinder 18 for operating circuit breaker 10 through a four-way control valve 31. This valve is arranged to control the closing of circuit breaker 10 by connecting source 27 with the right-hand end of cylinder 18 through conduit 32. For opening the circuit breaker, on the other hand, valve 31 is adapted to interconnect the source of fluid under pressure 27 with the left-hand end of cylinder 18 through conduit 33. Valve 31 is so constructed as to vent one end of cylinder 18 to atmosphere through conduit 34 whenever the other end of cylinder 18 is subjected to pressure from source 27. A suitable spring means 35 is provided to bias valve 31 to the closed position shown in the diagram. Valve 31 is arranged to be operated for opening circuit breaker 10 by means of an opening solenoid 36 which may be energized from any suitable control circuit. Similarly, valve 31 is arranged to be operated to control the closing of circuit breaker 10 by means of a closing solenoid 37 which may also be energized from any suitable control circuit. Blast valve solenoid 30, opening solenoid 36, and closing solenoid 37 are preferably controlled in the manner disclosed and claimed in copending application Serial No. 310,589 of Bryce W. Wyman, filed December 22, 1939, and assigned to the same assignee as the present application.

In the event that there is a reduction or complete failure of the pressure of source 27, it becomes impossible properly to operate circuit breaker 12. Even if means were provided other than the fluid-operated means disclosed for producing relative movement between contacts 11 and 12, without a sufficient fluid blast from conduit 16, the circuit could not be interrupted. In accordance with my invention, however, for the purpose of clearing the circuit in the event that circuit breaker 10 cannot be operated due to an inadequate pressure at the source 27, I provide auxiliary interrupting means 38, which preferably may comprise a high-tension fuse which has a circuit-interrupting capacity comparable with that of circuit breaker 10. This fuse or auxiliary circuit-interrupting means 38 is connected in series with terminal 15 of circuit

breaker 10 so that both circuit breaker 10 and auxiliary circuit-interrupting means 38 are connected in the main power circuit 39. Fuse 38 is normally shunted by a switch 40 which may be of the air break or any other suitable type and this switch is arranged to carry substantially all the current in power circuit 39 when in the closed position so that very little current passes through auxiliary circuit-interrupting means 38.

10 The switch blade of switch 40 is provided with an extension of insulating material 40a to which is attached a spring 41 so as normally to bias the switch 40 to the open position. This switch is adapted to be latched in its closed position by means of a latching element 42 pivotally mounted so as to engage with extension 40a. Latch 42 is controlled by means of solenoid 43, the energization of which causes clockwise rotation of latch 42, thereby releasing extension 40a whereupon 20 spring 41 moves switch 40 to the open position.

In order to make auxiliary circuit-interrupting means 38 effective to interrupt the circuit in the event that circuit breaker 10 cannot be operated and an abnormal current condition occurs in 25 power circuit 39, I provide a suitable control circuit for solenoid 43 which is energized when the pressure of the fluid at source 27 is insufficient to allow proper operation of circuit breaker 10. This control circuit includes a pressure-responsive relay 44 comprising a Sylphon bellows 45 connected to the source of pressure 27 and a suitable switch 46. Movement of Sylphon bellows 45 in response to the pressure of source 27 controls the operation of associated switch 46. The 30 control power for energizing solenoid 43 may be obtained from any suitable source, such as 47. When circuit breaker 10 is in the open position, it would, of course, be undesirable and unnecessary to open switch 40 in the event that pressure relay 44 operated in response to insufficient pressure at source 27 to close switch 46. Accordingly, limit switch 48 is provided to break the control circuit for solenoid 43 when circuit breaker 10 is in the open position. Switch 48 35 is connected with arm 23 and operated by movement thereof. In order to deenergize solenoid 43 after switch 40 has been opened, I provide a limit switch 49 operatively connected to extension 40a so as to be opened when switch 40 is opened. It will be understood that switch 40 may be closed and latch 42 reset by any suitable means after the pressure at source 27 has been restored to normal.

The operation of the circuit-interrupting system described above will be obvious to those skilled in the art since, if for any reason the pressure of the air or fluid in source 27 falls sufficiently so that it is undesirable or impossible to open circuit breaker 10 in the event of an 40 abnormal current condition, relay 44 will operate to close associated switch 46. Thereupon solenoid 43 is energized to release latch 42 from restraining switch 40 in the closed position whereupon fuse 38 is connected to carry all the current in power circuit 39 and the latter is protected even though circuit breaker 10 cannot be operated. By this arrangement, protection of the circuit is insured in all cases.

While I have shown and described a particular embodiment of my invention as applied to a circuit-interrupting system, it will be obvious to those skilled in the art that various changes and modifications may be made without departing from my invention in its broader aspects and I, therefore, aim in the appended claims to cover

all such changes and modifications as fall within the true spirit and scope of my invention.

What I claim as new and desire to secure by Letters Patent of the United States is:

1. A circuit-interrupting system comprising a source of fluid under pressure, a main circuit breaker for interrupting said circuit which depends for its operation at least to some extent upon said source of fluid under pressure, an auxiliary interrupting device, means normally maintaining said auxiliary interrupting device ineffective to interrupt said circuit, and means for controlling said last-mentioned means so that said auxiliary interrupting device becomes effective to interrupt the circuit when said source of fluid pressure is inadequate to operate said main circuit breaker properly.

2. A circuit-interrupting system comprising a source of air under pressure, a main circuit breaker which depends for its operation at least to some extent upon said source of air under pressure, an auxiliary interrupting device having a capacity comparable with that of said main circuit breaker, a switch normally shunting said auxiliary device thereby maintaining the latter ineffective, and means for opening said switch so that said auxiliary interrupting device becomes effective to interrupt the circuit when said source of air under pressure is inadequate to operate said main circuit breaker properly.

3. A circuit-interrupting system comprising a fluid-operated circuit breaker of the fluid-blast type for normally interrupting the circuit, a source of fluid under pressure for operating said circuit breaker and producing a blast of fluid for arc-extinguishing purposes, an auxiliary in-

terrupting device in said circuit having a capacity comparable with that of said circuit breaker, a switch normally shunting said auxiliary device, and means for opening said switch when said source of fluid pressure is insufficient to operate said circuit breaker properly.

4. A circuit-interrupting system comprising in combination a source of fluid under pressure, a main circuit breaker which depends for its operation at least to some extent upon said source of fluid under pressure, an auxiliary interrupting device having a capacity comparable with that of said circuit breaker connected in said circuit, a switch normally shunting said auxiliary device, a pressure-responsive relay associated with said source of fluid pressure for causing the opening of said switch to make said auxiliary interrupting device effective for interrupting said circuit when said source of fluid under pressure is inadequate to operate said main circuit breaker properly.

5. In combination, an electric circuit, means for normally interrupting said circuit in response to an abnormal electrical condition thereon, a source of fluid under pressure, said first-mentioned means being dependent at least in part upon fluid from said source for proper operation thereof, additional interrupting means for said circuit normally maintained ineffective to interrupt said circuit, and means responsive to a predetermined abnormal condition of said source of fluid for rendering said additional interrupting means effective to interrupt said circuit in response to an abnormal electrical condition thereon.

EUGENE W. BOEHNE.
